COMBINED POWER SUPPLY AND DIFFERENTIAL VOLTMETER

Benjamin Shmurak, Lynbrook, Albert E. Bleeker, Plainview, Edward Brenner, Commack, Maurice G. Paulson, Huntington, and Richard Projain, Jericho, N.Y., assignors to Lambda Electronics Corporation, Huntington, N.Y., a corporation of New York

Filed Mar. 21, 1969, Ser. No. 16,359

Term of patent 14 years

Int. Cl. D10—10

U.S. Cl. D26—1

FIG.1

FIG.2

FIG.3

FIG. 1 is a perspective view of a combined power supply and differential voltmeter embodying our new design showing the top, front and one side thereof;

FIG. 2 is a front elevational view of the combined power supply and differential voltmeter of FIG. 1; and

FIG. 3 is a perspective view of the combined power supply and differential voltmeter of FIGS. 1 and 2 showing the bottom, rear and one side thereof.

We claim:

The ornamental design for a combined power supply and differential voltmeter, as shown.
